UNITED STATES PATENT OFFICE.

MELVIN STRINGER, OF POTTSTOWN, PENNSYLVANIA.

METHOD OF FORMING BAND BRAKES.

Original application filed August 28, 1924, Serial No. 734,698. Divided and this application filed October 19, 1925. Serial No. 63,534.

My invention relates to improvements in sheet metal stampings, and more particularly has reference to the stamping of angle split rings such as are especially adapted 5 for use in band brakes for vehicles such as automobiles.

It has been customary heretofore to make these angle rings of cast iron which is not entirely satisfactory, and in the few instances 10 where they have been stamped, sheet steel discs are first punched, and out of each of said discs is thereafter punched another smaller disc, leaving a flat ring which may then be re-stamped to provide a flange of 15 angle form in cross-section. This method of procedure, however, is not only very wasteful of material, but also of labor, and also results in the construction of an angle band or split ring which is not sufficiently 20 uniform.

In the accompanying drawings, I have illustrated in Fig. 1 in longitudinal section, an application of a split ring in position in a suitable form of die, showing the manner 25 of making the first turn of the flange thereof. Fig. 2 indicates a cross-sectional view of the product so formed. Fig. 3 shows a strip of unformed metal in plan view. Fig. 4 is a front view of the dies 30 in position making the second operation. Fig. 5 is a cross-sectional view of the ring after the second operation.

According to the preferred embodiment of my invention, when a split angle band of 35 the character described is to be made, a long narrow strip of material which is first rolled to the proper diameter is thereafter stamped in two operations, the first of which partly turns the flange, and the second of 40 which completely turns the flange, forming an angle split ring in more uniform manner, much more quickly, and with practically 45 no waste of material, also producing a product which is practically clear of all irregularities, and of great uniform strength.

In my co-pending patent application, #734,698, filed August 28, 1924, I have illustrated a suitable form of mechanism adapted 50 to perform the several operations above referred to, this application being in the nature of a division thereof, and being intended to cover more particularly the method described, as distinguished from the mechanism adapted for use in the practice 55 of said method.

Said mechanism is also illustrated herein and will be understood from the following:—

11 indicates the base block of the die which is provided with a ring 12 normally projected upwardly by any suitable means such as the springs 13 around the bolts 14 which are preferably secured in the base block 11 in any convenient manner as shown. The top of the base block is circular in 60 cross-section and is provided with an annular seating for the split ring or hoop of steel such as 15. 16 indicates the upper part of the die which it will be observed continuing upwardly with a bevel or angle 17, 65 preferably at about forty-two degrees. When the split ring 15 is placed in position upon the block 11 as shown in full outline and the upper part 16 of the die is brought down upon the same, the upper portion of 70 the ring is bent inwardly as indicated at 18, producing a slight curvature, as shown to better advantage in Fig. 2. After the bands have been thus shaped, the upper part of 75 the die is changed, and the upper part 19, 80 shown to advantage in Fig. 4, is substituted. This part of the die it will be observed is provided with a flat portion 20 at right angles to the vertical wall of the band, and when the same is brought down upon the 85 band as shown in Fig. 4, the flange is formed at right angles as indicated at 21 in Fig. 5. In a band thus formed it will be 90 found that the walls are substantially uniform throughout showing practically no wrinkles or crowding of material, and are of uniform strength.

Of course it will be understood that various modifications may be made in the various steps and the order of the same in the 95 practice of the invention.

I claim:—

1. The method of forming an article of the class described consisting in first forming a strip of material to the desired diameter, then bending the upper part in a stamping press forming a flange part of the distance said flange is to be bent, and then thereafter completing the bending of said flange with another tool. 100

2. The method of forming an article of the class described consisting in first forming a strip of material to the desired diameter, then bending the upper part in a stamping press forming a flange part of the 105 110

distance said flange is to be bent, and then thereafter completing the bending of said flange with another tool, the first tool having a beveled engaging wall and the second tool having a straight engaging wall.

3. The method of forming an article of the class described consisting in first forming a strip of material to the desired diameter, then bending the upper part in a

stamping press forming a flange part of the 10 distance said flange is to be bent, and then thereafter completing the bending of said flange with another tool, and holding the strip during the forming operation.

In testimony whereof I hereunto affix my 15 signature.

MELVIN STRINGER.
